[57] CLAIM

The ornamental design for a latch for closing a shoe by pulling eyelets together, as shown and described.

DESCRIPTION

FIG. 1 is a top plan view of a latch for closing a shoe by pulling eyelets together showing my new design;
FIG. 2 is a left end elevational view thereof;
FIG. 3 is a right side elevational view thereof, the left side elevational view being the mirror image thereof;
FIG. 4 is a right end elevational view thereof; and
FIG. 5 is a bottom plan view thereof.

FIG. 1

FIG. 2

FIG. 3

FIG. 4

FIG. 5
